(57) **CLAIM**

The ornamental design for an oval bottomrail for a shade structure, as shown and described.

DESCRIPTION

FIG. 1 is a front perspective view illustrating my design for a oval bottomrail for a shade structure;

FIG. 2 is a front view thereof;

FIG. 3 is a left side view thereof;

FIG. 4 is a top view thereof;

FIG. 5 is a right side view thereof;

FIG. 6 is a bottom view thereof; and,

FIG. 7 is a rear view thereof.

The broken lines in the drawings are included for purposes of illustrating portions of the oval bottomrail for a shade structure, but form no part of the claimed design.
